UNITED STATES PATENT OFFICE.

ISABELLE P. McDONALD AND WILLIAM MACMULLEN, JR., OF DULUTH, MINNESOTA,
ASSIGNORS TO F. A. PATRICK & CO., OF DULUTH, MINNESOTA, A CORPORATION OF
MAINE.

GARMENT.

Application filed February 7, 1927. Serial No. 166,477.

This invention relates to improvements in garments, and has special reference to a union overgarment particularly designed for use by children.

5 The principal object is to produce a more simple and efficient garment of this character than heretofore known.

Another object is to provide a novel form 10 of interlocking termini of the seat flap to as nearly as possible prevent the ingress of snow, water or the like.

Other objects and advantages of the peculiar construction will appear in the further description thereof.

15 Referring now to the accompanying drawing illustrating a perspective view of one of the garments, partly in section, and showing one embodiment of the invention, like reference characters indicating like parts:

20 The garment is preferably made of heavy closely woven material, suitable for outing purposes, and designed with a full belt 1 around the waist thereof and stitched directly to the garment from slightly forward 25 of each side opening completely about the back thereof and closely adjacent the upper edge, as indicated at 2.

The seat flap is indicated at 3 and terminates on either side of the garment in a side 30 flap 4 extending inwardly of the marginal edge of each side opening. The side openings are reinforced in the usual manner as indicated at 5 and the lower terminus of each side flap 4 is securely stitched inwardly of 35 the front part of the garment to its juncture with the side edge of the opening as indicated at 6. A waist flap 7 is formed beneath the belt 1 by an upwardly extending notch or cut 8 forming a continuation of the side

40 openings of the front portion of the garment for cooperative engagement with the side flaps 4 in perfecting a complete closure, and for which purpose a button hole 9 is formed

adjacent the edge of the side openings above the lower edge of the waist flap, preferably 45 in line with the buttons 10 on said flap, so that when the seat flap 3 is raised into position and buttoned (it having a row of suitable holes adjacent the edge thereof for such purpose) to the buttons 10, the upper outer 50 corners thereof, which are the upper corners of the side flaps 4 previously referred to, will extend through the notches or slots 8 in direct line with the buttonholes 9 where they may be conveniently buttoned prior to 55 the buttoning of the lower one or more on each side flap 4 as desired.

In this manner a most convenient seat flap is provided, and one which when securely 60 buttoned not only overlaps the waist flap, but extends inwardly of the body portion of the garment and buttons thereto above the marginal edges of the waist flap, which 65 union is wholly covered by the permanently fixed portion of the waist band or belt.

Having thus described our invention, what we claim and desire to secure by Letters Patent, is:

A garment of the character described having in combination therewith a belt securely 70 stitched along the upper edge thereof about the back portion of the waist line, a waist flap beneath the belt about the back of the garment having slits upon either side thereof and extending above its lower marginal 75 edge, a seat flap having its upper termini engageable through said slits, means for attaching the upper edge of the seat flap to the waist flap, and means for uniting the upper corners of the seat flap to the body 80 portion of the garment forwardly of the slits.

In testimony whereof we affix our signatures.

ISABELLE P. McDONALD.
WILLIAM MACMULLEN, JR.
